FOLDING CARTON

Earl B. Whitehead, Norwich, Conn., assignor to
 Atlantic Carton Corporation, Norwich, Conn.,
 a corporation of Connecticut

Application July 31, 1933, Serial No. 683,041

2 Claims. (Cl. 206—45)

This invention relates to improvements in boxes and is directed more particularly to improvements in foldable cartons.

One object of the invention is the provision of a box which may be easily and quickly folded either into a display position or a shipping position as may be desired. As a further object, the box of the invention is provided with means for forming a tier or tiers for supporting articles in relatively raised positions in the box. The box is simple and economical to manufacture and is secure and strong in both display and shipping positions.

The invention will be more fully described in connection with the accompanying drawing, wherein

Fig. 1 is a plan view of the carton of the invention in knock-down position.

Fig. 2 is a perspective view of the carton in display set-up position.

Fig. 3 is a transverse sectional elevational view of the box in display set-up position.

Fig. 4 is a small-scale sectional elevational view of the box arranged for shipping.

Fig. 5 is a small-scale plan view of the bottom of the box shown in Fig. 4.

Fig. 6 is a partial plan view of a modified form of the invention in knock-down position, and

Fig. 7 is a small scale partial sectional elevational view of the box of Fig. 6 in set-up position.

Referring to the drawing more in detail, the invention will now be described.

The box shown in knock-down position in Fig. 1 has a front wall 2, a rear wall 4 and side walls 6. The walls are hingedly connected at their side marginal edges and the side walls 6 preferably have their upper marginal edges sloping as shown for reasons which will shortly appear.

To the upper marginal edge of the rear wall 4 is hinged a top flap member 8 which is adapted to close the top of the box. This member 8 is preferably scored to provide three sections as shown in Fig. 1 so that it may serve also as a display panel.

45 The foremost of these sections may be called a front tab portion 10 and is adapted to lie adjacent the inside of the front wall 2 when the box is in shipping position, as shown in Fig. 4, and adjacent the inside of the rear wall 4 when the box is in display position, as shown in Fig. 3. A section 12 of the flap may be called a panel section and is that section adjacent the wall 4. An intermediate section 14 connects the panel section 12 to the front tab 10 and together with the section 12 serves to cover the top of the box

when it is in shipping position. The sections 12 and 14 are foldable along the scored lines to lie adjacent one another when the box is in set-up position as shown in Fig. 3.

If desired, section 12 may be cut as at 13 to provide a panel flap 15. In this way, when the box is in display position the portion 15 will extend upwardly as shown. Thus is provided a novel top flap which not only serves to close the top of the box when it is to be used for shipping but which serves as a distinctive display panel when the box is in set-up position.

My novel means of supporting articles in the box when in set-up position will now be described.

To the lower marginal edge of one of the walls is hinged what may be called a bottom flap member 30. This flap is adapted to extend across the bottom of the box and has on its forward end a tab portion 32 which, when the box is in set-up position either for shipping or display, may lie adjacent the inside of that wall of the box which is opposite the wall to which the flap 30 is hinged.

The bottom member 30 is provided with an opening 34 intermediate its opposite ends which functions in a manner which will soon appear.

To the lower marginal edge of the wall of the box, which is opposite the wall to which the bottom flap is connected, is hinged a tier-forming flap member 20. This flap is scored so as to provide certain foldable sections which may be so disposed as to form tiers on which articles within the box may be supported.

The section of the flap 20 nearest the wall to which it is hinged may be called a connecting section 22. To this is hinged a spacer section 24, which in turn is connected to a supporting section 26. Another spacer section 28 may be connected to the other side of the supporting section 26 and is of course preferably of the same width as the spacer 24. In this way, the flap 20 may be folded as shown in Fig. 3 so that a tier is formed, preferably adjacent the rear of the box. Thus articles such as boxes B may be supported in relatively raised positions as shown.

When it is desired to have the box in shipping position, the tier-forming flap member 20 may be folded and inserted in the opening 34 to lie adjacent the bottom flap 30, as shown in Figs. 4 and 5. In this way a compact and novel shipping container is provided.

In the preferred form of the invention, the other two walls of the box, which in the form shown in Fig. 1 happen to be the side walls 6, have relatively small flaps 7 hinged to their

55

lower marginal edges. These flaps are not essential to the novelty of the box but contribute to its strength and security in that they are adapted to fold under and lie adjacent the insides 5 of the flaps 20 and 30.

It is now desired to point out that the tier-forming flap may be provided with as many supporting sections as desired, it only being desirable however that there be a corresponding 10 number of openings in the bottom flap.

In the modified form of the invention shown in Figs. 6 and 7 the carton has a front wall 2' a rear wall 4' and side walls 6'. Side flaps 7' are hinged to the lower marginal edges of the 15 walls 6'. A bottom flap member 40 is shown hinged to the rear walls 4' and is provided with spaced openings 42 and 44. A tier-forming flap 50 is hingedly connected to the front wall 2' and consists of a plurality of sections similar to 20 the form previously described.

Adjacent the wall 2' is a connecting section 53 and to it is hinged a spacer section 56. A supporting section 52 has one side connected to this section 56 and its opposite side connected to a 25 spacer section 58. Another connecting portion 55 connects the last-named spacer 58 to a spacer 57 while a second supporting tab 54 is hinged at its 30 opposite sides to spacers 57 and 59.

In this way, the flap 50 may be folded as shown 35 in Fig. 7 so that its connecting portions 53 and 55 lie adjacent the outside of the bottom flap 40 with the supporting sections 52 and 54 supported within the openings 42 and 44 by the two pairs of spacers 56 and 58 and 57 and 59 respectively. 40 In the preferred form of the invention, the last spacer section such as 59 will lie adjacent the 35 inside of the rear wall as shown.

It is a novel feature of this invention, but it is 45 not desired to be limited thereby, that the supporting sections such as 52 and 54 vary in height, preferably those supporting sections in the rear of the box being higher than those at the forward end, so that articles such as boxes B may be displayed more attractively and seen more readily. 50 This may be accomplished of course by varying the widths of the spacer sections. To this end then, the spacers 56 and 58 which support the forward supporting section 52 are shown to be less in width than the spacers 57 and 59 which support the rear supporting section 54.

The widths of the connecting portions such as 53 and 55 may vary, it being preferable of course 55 that they be at least the width of the distances between the openings such as 42 and 44 of the bottom flap.

With the upper marginal edges of the side walls 6 sloping forwardly as stated and the rearward tiers being higher than the forward ones, articles such as B may be supported in the manner shown 60 in Fig. 2. According to the preferred form of the invention articles are also supported by the forward part of the bottom flap as shown and

when the carton is arranged for shipping all the articles are brought into the same plane with those articles supported by the bottom flap.

If desired, the front wall such as 2 may have a portion cut out as shown so that the foremost 5 articles are better displayed.

While I have described my invention in great detail and with respect to preferred embodiments thereof, I do not desire to be limited to such detail or embodiments since many changes 10 and modifications may be made without departing from the spirit and scope of the invention in its broader aspects. Hence, what I desire to claim as new and secure by Letters Patent of the United States is:

1. A foldable shipping and display box of the class described comprising in combination, vertically-extending front and rear walls of equal width hingedly connected by side walls of equal width, a bottom closure flap member substantially 20 equal in width to said front and rear walls having a main body portion for extending in a substantially horizontal position between the lower marginal edges of said walls and a tab portion for lying adjacent the inside of said front wall, said body portion being provided with an opening 25 therein, and a foldable tier-forming member hingedly connected to the lower marginal edge of said front wall and scored along certain lines parallel with said lower marginal edge of the 30 front wall to include successively a connecting section adjacent said front wall for lying adjacent the outside of said bottom flap member, a spacer section for extending upwardly within said opening at substantially right angles to said bottom flap member, a supporting section for 35 extending in substantial parallelism with and above said bottom flap and another spacer section for extending in parallelism with said first spacer section.

2. A foldable shipping and display box of the class described comprising in combination, vertically-extending front and rear wall members hingedly connected by side walls, a bottom flap member hingedly connected to the lower marginal edge of one of said wall members for extending in a substantially horizontal position between the lower marginal edges of said wall members and provided with an opening therein, and a foldable tier-forming member hingedly connected to the lower marginal edge of the opposite wall member and scored along certain lines parallel with the lower marginal edges of the wall members to include successively a connecting section for lying 50 adjacent the outside of said bottom flap, a spacer section for extending upwardly within said opening, a supporting section for extending in parallelism with said bottom flap and another spacer section for extending in parallelism with said first spacer section.

EARL B. WHITEHEAD.
